UNITED STATES PATENT OFFICE.

RUDOLF E. HELLMUND, OF SWISSVALE, PENNSYLVANIA.

SYSTEM OF CONTROL FOR SINGLE-PHASE ALTERNATING-CURRENT MOTORS.

1,339,928.

Specification of Letters Patent.

Patented May 11, 1920.

Application filed June 15, 1917. Serial No. 174,885.

To all whom it may concern:

Be it known that I, RUDOLF E. HELLMUND, a subject of the Emperor of Germany, and a resident of Swissvale, in the 5 county of Allegheny and State of Pennsylvania, have invented a new and useful Improvement in Systems of Control for Single-Phase Alternating-Current Motors, of which the following is a specification, this 10 application being a continuation in part of application Serial No. 33,481, filed June 11, 1915.

My invention relates to systems of control for alternating-current motors of the doubly-fed compensated commutator type, and it has for its object to provide a system of the character described containing two or more motors wherein relatively few control switches are employed, relatively few 20 terminal leads are necessary, and wherein the control switches shall operate solely in circuits carrying only a portion of the full-load armature current of one of the motors.

In the accompanying drawing, Figures 25 1, 3, 10, 12 and 14 are diagrammatic views of compensated commutator motors, together with their attendant supply and control circuits, constructed in accordance with different embodiments of my invention; Figs. 2, 4, 11, 13 and 15 are sequence charts 30 illustrating the mode of switch operation in the accompanying circuits; and Figs. 5 to 9, inclusive, are simplified diagrammatic views of the motor and system shown in 35 Fig. 1, illustrating in greater detail the method of acceleration employed therein.

In the development of the alternating-current commutator motor, especially for traction purposes, it has been found necessary, especially where resistance leads are dispensed with, to provide compensating windings for controlling the commutation. Many advantages pertain to what is known as the doubly-fed motor, wherein either an 40 interpole or a compensating winding is connected in series with the main field and armature windings and a tap is provided from a point intermediate the compensating field winding and the remainder of the motor to 45 the source, so that the voltage impressed upon the compensating field winding shall have a value complementary to that of the voltage impressed upon the remainder of the motor windings. It has been found desirable 50 to provide the compensating or cross-field winding with more turns than the ar-

mature winding so that, as a result of the transformer action therebetween the cross-field winding shall carry smaller currents than the armature winding, the differential 60 current reaching the source via the intermediate or tap connection. With a motor of the character described, when it is desired to entirely disconnect from the source 65 relatively small switches may be employed in the connections between the terminals of the cross-field winding and the source because each of these connections carries only a portion of the load current, but relatively 70 large switches are required in the connection from the other terminal of the motor to the source because full-load armature current is here encountered.

By my invention I employ two or more 75 motors of the characters indicated, preferably of similar size and operating characteristics, connecting both terminals of both cross-field windings to the current source through suitable control means and connecting the remaining motor terminals directly 80 together. By this connection, assuming instantaneous values, a portion of the load current flows into the outer terminal of the cross-field winding of one motor and the remainder of the load current flows into said 85 motor via its intermediate connection. After passing through said motor, the entire load current flows through the armature and main field winding of the other motor and then divides, a portion passing back to 90 the source via the intermediate connection and the remainder via the cross-field winding of the last motor. By placing all of the 95 control switches in the connections to the source, I am enabled to dispense entirely with control switches which carry full-load armature current and, at the same time, I obtain an exceedingly simple and flexible system of voltage control for the motors. An intermediate or neutral connection is 100 preferably provided from a point intermediate the two motors to a point of corresponding potential in the source, said neutral connection normally being disconnected or carrying only unbalanced currents but providing means whereby, in case of emergency, either motor may be entirely disconnected and the railway vehicle operated 105 solely by the remaining motor.

By my invention, the voltages impressed 110 upon the cross-field windings of the two motors may be somewhat different for cer-

tain accelerating notches, but nevertheless, the motors will exert the same torque because the armatures are connected in series and are therefore supplied with the same current and, further, because of the transformer effect between each armature and its associated cross-field winding, whereby each of the latter will also have practically the same current as the other. The different voltages impressed upon the cross-field windings will slightly alter the compensating effect and the commutating conditions in the two motors but not sufficiently to have any practical importance. My invention comprises further details and modifications along the above-mentioned lines, as will hereinafter more fully appear.

Referring to Fig. 1 for a more detailed understanding of my invention, I have shown two motors of the compensated commutator type at 14 and 15. The motor 14 is provided with an armature 16, a main-field winding 17 and a cross-field winding 18 and, in like manner, the motor 15 is provided with an armature 19, a main-field winding 20 and a cross-field winding 21. Current for the motors 14 and 15 is derived from any suitable source, such, for example, as the secondary winding 22 of a transformer 23. Energy is supplied to the outer terminal of the cross-field winding 18 through a control switch 1. The voltage of the other terminal of the cross-field winding 18 may be adjusted by suitable control switches 2, 3 and 4 and a preventive device 24 of the usual form. The outer terminal of the cross-field winding 21 is connected to the transformer winding 22, not only through a control switch 9 but also through a resistance member 25 which may be short circuited by a switch 10. The voltages impressed upon the inner terminal of the cross-field winding 21 may be adjusted by suitable control switches 6, 7 and 8 and a preventive device 26. The armature windings 16 and 19 and the main field windings 17 and 20 are all connected in series relation between the inner terminals of the cross-field windings 18 and 21. The direction of current flow through the main field windings, with respect to the armature windings, may be reversed by a suitable switch 27 when desired. For repulsion operation, the armature windings 16 and 19 may be short circuited through a resistance member 28 and a switch 5.

Having thus described the arrangement of the circuit shown in Fig. 1, the operation is as follows, referring to the sequence chart of Fig. 2 and Figs. 5 to 9, inclusive. At the outset, switches 1, 5 and 9 are closed, (Fig. 5) whereupon the motors 14 and 15 are connected for repulsion operation with a minimum impressed voltage, and the resistance member 25 is included in circuit. The re-

sistance member 25 is then eliminated by closing the switch 10, thus providing the first running position (Fig. 6). The voltage applied to the cross-field windings 18 and 21 is then raised by a suitable manipulation of the switches 2, 3, 4, 6, 7 and 8, and the repulsion connection through the switch 5 is opened, whereupon the motors are connected for the second running position for doubly-fed operation (Fig. 7). The voltage impressed upon the cross-field windings 18 and 21 is then reduced by even steps, the voltage on the armatures 16 and 19 and the main field windings 17 and 20 being raised accordingly. (Figs. 8 and 9.)

As ordinarily designed, the cross-field windings 18 and 21 would contain substantially twice the number of turns included in the armature windings 16 and 19. Accordingly, substantially one-half the working current would flow through the switches 1 and 9 and the other half would flow through the switch 2 or the switch 4 and through the switch 6 or the switch 8. None of the control switches therefore are ever called upon to open circuits carrying full-load current.

Referring to the form of my invention shown in Fig. 3, two motors 14 and 15 are provided and are connected, in a general manner, similar to that shown in Fig. 1, with the exception that the main field windings 17 and 20 are normally connected directly between the armatures 16 and 19 through individual reversing switches 27 and 28, disconnecting switches 29 and 30 and the actuating windings of a limit switch 40 connected to operate the control switches of the associated motors in accordance with any of the known systems of automatic limit-switch control.

Each of the switches 29 and 30 is provided with an emergency contact member 42. The emergency contact member of the switch 29 is connected, through the actuating winding of a limit switch 44 to the tap 6 and, in like manner, the emergency contact member of the switch 30 is connected, through the actuating winding of a limit switch 43, to the tap 4. The contact members of the limit switch 44 are connected in series with one pair of those of the limit switch 40, and those of the limit switch 43 in series with the other pair of those of the limit switch 41. The switches 43 and 44 are preferably given higher settings than the switch 40.

Under normal conditions, the potentials and currents in the system will be in a state of equilibrium, and current will flow across directly from the switch 29 to the switch 30. If a motor, such, for example, as 14, is disabled, the switch 30 is thrown to the emergency position, whereupon the motor 15 is connected for doubly-fed operation between the taps 4 and 9. The motor 15 therefore receives a greater impressed voltage

than that encountered in normal operation, the latter voltage being substantially half of that between the taps 1 and 9. During normal operation, the actuating winding of the limit switch 43 was unenergized, so that said switch remained in the closed position and exerted no influence in the control circuit. With the emergency connection, however, the energizing winding of the switch 10 40 is deenergized and the limit switch 43 comes into operation and, with its higher setting and series connection with the contacts of the switch 40, supersedes the latter in function and assumes control of the 15 switches 5, 6, 7, 8 and 9. It will thus be seen that, when operating on one motor, a greater voltage and a greater current are impressed thereupon than in normal operation, resulting in the development of the 20 necessary torque.

It will be observed that, because of the desired segregation between the two motors, it is impossible to provide a common repulsion connection for the two armatures and 25 I therefore provide the respective armature windings with short-circuiting resistance members 28 and 28' that are controlled, respectively, by suitable switches 5 and 5'.

It will be further noted that, with the 30 circuit shown in Fig. 3, it is necessary to provide each motor with but five leads, as compared with the six leads commonly employed hitherto in like relations.

The present disclosure differs from that 35 set forth in the above-identified application, of which this is a continuation in part, in the arrangement and connections of the current relays 40, 43 and 44.

The system shown in Fig. 10 is, in many 40 respects, the same as that shown in Fig. 1 but an additional accelerating step and low-speed running position is obtained by first passing current through the armature windings 16 and 19 in the reverse direction from 45 that employed in normal operation, thus obtaining what may be termed a sub-repulsion or reverse doubly-fed connection. The motors are subsequently accelerated in the manner indicated in Fig. 1.

50 Referring to the form of my invention shown in Fig. 12, the connections are the same as shown in Fig. 1 with the exception that the voltage supplied by the outer tap 32 may be adjusted by suitable switches 9, 55 53 and 54 and a preventive device 33. As pointed out in the preliminary explanation, the effect of the unbalancing thus produced in the system is largely eliminated by reason of the fact that the armature windings 16 and 19 are connected in series with each other and therefore carry the same current, and each of them is inductively related to its associated cross-field winding.

Under certain conditions, I find it highly 60 desirable to maintain an even voltage bal-

ance in the system at all times and to effect a portion of the voltage control, under normal operation, by manipulating transformer turns in the central portion of the secondary winding. If then, for any reason, it becomes necessary to disconnect one of the motors, the above mentioned central group of control switches is available for the speed control of the remaining motor, providing additional steps and rendering possible the 70 application of a voltage higher than normal thereto in accordance with the principles pointed out in connection with Fig. 3. I therefore connect as shown in Fig. 14, wherein the two motors 14 and 15 are arranged to derive energy from a secondary winding 22 split into halves 22' and 22''. The motors 14 and 15 are normally connected in series relation through disconnecting switches 29 and 30, and a neutral 80 wire 31 is rendered inoperative because of the open position of suitable emergency control switches 36 to 41, inclusive. The adjacent terminals of the windings 22' and 22'' may be directly connected through a switch 90 55 or indirectly connected through a switch 56 and resistance members 42 and 43. The taps 44 and 45, symmetrically located in the windings 22' and 22'' may be directly connected through a switch 57. 95

As shown in the sequence chart of Fig. 15, the switch 57 is closed at the outset, thus eliminating the winding portions 34 and 35 and reducing the voltage supplied to the switches 4 and 6 to a minimum value. At 100 the fourth accelerating position, the switch 56 is closed, whereupon a larger number of turns is included between the switches 4 and 6 but the current is reduced in value by the resistance members 42 and 43. At the 105 sixth accelerating position, the resistance members 42 and 43 are eliminated by closing the switch 55, whereupon the maximum voltage is obtained between the switches 4 and 6. The voltage supplied to the intermediate taps and outer terminals of the doubly-fed motors 14 and 15 is adjusted in the usual manner by the manipulation of the switches 1 to 4, inclusive, 6, 7, 8 and 9. 110

If now, for example, the motor 15 is disabled, the corresponding disconnecting switch 30 is opened, and the vehicle is operated by the motor 14 through the neutral wire 31 and the emergency switches 36 to 41, inclusive. When low operating voltage 120 is required, the switch 38 is closed, and only the voltage between the taps 1 and 44 is employed. When a greater voltage is desired, the closing of the switch 36 causes the entire winding 22' to be active, but its effective 125 voltage is cut down by the member 42. Further voltage increase is next obtained by closing the switch 37, connecting the winding 22' directly in circuit. In the final operating condition, to obtain abnormal voltage 130

on the motor 14, the switch 41 or the switches 38 and 57 are closed, thus adding the voltage of the winding 35 to that of the half secondary member 22. The switches 5 1, 2, 3 and 4 are also employed, in the usual manner, during emergency operation of the motor 14.

While I have shown my invention in a variety of modifications, it will be apparent 10 to those skilled in the art that it is susceptible of various minor changes and modifications without departing from the spirit thereof, and I desire, therefore, that only such restrictions shall be placed thereupon 15 as are imposed by the prior art or are specifically set forth in the appended claims.

I claim as my invention:

1. In a system of control, the combination 20 with a supply-transformer winding and a plurality of alternating-current motors of the commutator type severally having armatures, exciting and inducing field windings, of means for connecting the armatures and exciting field windings of all motors in series 25 relation across a middle section of the transformer winding, and means for connecting each of said inducing field windings across an adjusting outer transformer section contiguous to said middle section, whereby the 30 voltage of all motors may be changed by successively and independently varying the voltage of said inducing field windings.

2. In a system of control, the combination 35 with a supply-transformer winding and a plurality of alternating-current motors of the commutator type severally having armatures, exciting and inducing field windings, of means for connecting certain of the windings of all motors in series relation across 40 a middle section of the transformer winding, means for connecting the remaining wind-

ings across outer transformer sections contiguous to said middle section, a limit switch normally connected in the series circuit, a plurality of normally disconnected limit 45 switches, and cut-out means for simultaneously cutting-out any one motor together with said normally connected limit switch and cutting-in one of said normally disconnected limit switches to permit complete 50 operation of another motor.

3. In a system of control, the combination with a supply-transformer winding and a 55 plurality of alternating-current motors of the commutator type severally having armatures, exciting and inducing field windings, of means for connecting the armatures and exciting field windings of all motors in series relation across a middle section of the transformer winding, and means for connecting the inducing field windings across outer transformer sections contiguous to 60 said middle section, a limit switch normally connected in the series circuit, a plurality of normally inoperative limit switches of 65 higher setting than said normally connected limit switch and each having one terminal connected to one of two points located predetermined distances on the respective sides of the transformer electrical mid-point, and a plurality of cut-out switches for simultaneously cutting-out the respective motors, together with said normally connected limit switch, and cutting-in one of said normally disconnected limit switches to thus permit 70 complete operation of another motor from more than half of the transformer winding.

In testimony whereof I have hereunto subscribed my name this 26th day of May, 1917.

RUDOLF E. HELLMUND.
